[57] CLAIM

The ornamental design for an electrode pad for an electrocardiograph, substantially as shown and described.

DESCRIPTION

FIG. 1 is a front elevational view of an electrode pad for an electrocardiograph showing our new design;
FIG. 2 is a rear elevational view thereof;
FIG. 3 is a side elevational view thereof;
FIG. 4 is a top plan view thereof;
FIG. 5 is a bottom plan view thereof;
FIG. 6 is a top perspective view thereof;
FIG. 7 is a bottom perspective view thereof.

FIG.1

FIG.4

FIG.2

FIG.5

FIG.3

FIG.6
